CLAIM

The ornamental design for a rifle rest, as shown and described.

DESCRIPTION

FIG. 1 is a perspective view showing my new design for a rifle rest;

FIG. 2 is a front elevational view;

FIG. 3 is a rear elevational view;

FIG. 4 is a left side elevational view;

FIG. 5 is a right side elevational view; and

FIG. 6 is a top plan view; and,

FIG. 7 is a bottom plan view.

The broken line drawings of FIGS. 1-7 are for illustrative purposes only showing adjustment knobs and form no part of the claimed design.
